UNITED STATES PATENT OFFICE

159,558

BILLIARD BALL TRIANGLE

Carl A. Sundell, Muskegon, Mich., assignor to The Brunswick-Balke-Collender Company, Chicago, Ill., a corporation of Delaware

Application April 5, 1948, Serial No. 145,522

Term of patent 14 years

(Cl. D34—3)

To all whom it may concern:

Be it known that I, Carl A. Sundell, a citizen of the United States, residing at Muskegon, in the county of Muskegon, State of Michigan, have invented a new, original, and ornamental Design for a Billiard Ball Triangle, of which the following is a specification, reference being had to the accompanying drawings, forming a part thereof.

Fig. 1 is a perspective view showing the new billiard ball triangle;

Fig. 2 is a plan view thereof;

Fig. 3 is an end elevation thereof; and

Fig. 4 is a section taken along line 4—4 of Fig. 2.

I claim:

The ornamental design for a billiard ball triangle, as shown.

CARL A. SUNDELL.
